(57) **CLAIM**

The ornamental design for a combined lighter holder with cigar splitter and keychain holder, as shown and described.

DESCRIPTION

FIG. 1 is a side perspective view of a combined lighter holder with cigar splitter and keychain holder showing our new design.

FIG. 2 is a right side elevation view thereof.

FIG. 3 is a left side elevation view thereof.

FIG. 4 is a front elevation view thereof.

FIG. 5 is a rear elevation view thereof.

FIG. 6 is a bottom plan view thereof.

FIG. 7 is a top plan view thereof.

FIG. 8 is a cross-sectional view thereof taken along line 8-8 of FIG. 1; and,

FIG. 9 is cross-sectional view thereof taken along line 9-9 of FIG. 4.

The broken lines shown in FIGS. 1, 4, 5, 8 and 9 represent portions of the article for which protection is not sought.

1 Claim, 3 Drawing Sheets
